(57) **CLAIM**

The ornamental design for a packaging set with components as shown and described.

DESCRIPTION

FIG. 1 is a front, right, top perspective view of a first component of a packaging set with components, showing the new design;

FIG. 2 is rear, left, bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of a second component of a packaging set with components;

FIG. 10 is a front elevation view thereof;

FIG. 11 is a rear elevation view thereof;

FIG. 12 is a left side view thereof;

FIG. 13 is a right side view thereof;

FIG. 14 is a top plan view thereof;

FIG. 15 is a bottom plan view thereof;

FIG. 16 is a front, right, top perspective view of a third component of a packaging set with components;

FIG. 17 is a front elevation view thereof;

FIG. 18 is a rear elevation view thereof;

FIG. 19 is a left side view thereof;

FIG. 20 is a right side view thereof;

FIG. 21 is a top plan view thereof;

FIG. 22 is a bottom plan view thereof;

FIG. 23 is a front, right, top perspective view of a packaging set with components, shown in an assembled configuration; and,

FIG. 24 is an exploded perspective view thereof, wherein the first component shows a set of two, the second component shows a set of two, and is shown in an open configuration. The broken lines of uneven length illustrate boundary lines that form no part of the claimed design. The broken lines of equal length represent parts of the article forming no part thereof.
